(57) **CLAIM**

The ornamental design for a light-emitting diode, as shown and described here.

DESCRIPTION

FIG. 1 is a top perspective view of a light-emitting diode showing our new design, with an upper surface, a front side surface and a right side surface shown;

FIG. 2 is a bottom perspective view showing a bottom surface with rear and left side surfaces;

FIG. 3 is a front elevation view thereof;

FIG. 4 is a rear elevation view thereof;

FIG. 5 is a top plan view thereof;

FIG. 6 is a bottom plan view thereof, opposite the view of FIG. 5;

FIG. 7 is a right side elevation view thereof; and,

FIG. 8 is a left side elevation view thereof.
